UNITED STATES PATENT OFFICE.

HUGH M. ROCKWELL, OF BRISTOL, CONNECTICUT, ASSIGNOR, BY MESNE ASSIGNMENTS, TO THE MARLIN FIREARMS CORPORATION, OF NEW HAVEN, CONNECTICUT, A CORPORATION OF DELAWARE.

AUTOMATIC GUN.

Application filed January 17, 1919, Serial No. 271,741. Renewed August 7, 1925.

To all whom it may concern:

Be it known that I, HUGH M. ROCKWELL, a citizen of the United States, and a resident of Bristol, in the county of Hartford and State of Connecticut, have invented certain new and useful Improvements in Automatic Guns, of which the following is a specification.

Because of the many advantageous features, automatic guns of the type generally known as the heavy Browning have been used in connection with airplanes. It was found, however, that this gun possessed certain arrangements of parts that prevented the obtaining of the full efficiency of the gun in airplane work.

Automatic guns, when mounted on an airplane for use by the observer, are usually carried by a so-called turret and are so supported as to be capable of firing in any direction. The observer's pit is not of very great diameter and the butt of the gun extends some distance therein. A gun, such as the heavy Browning, which has its handle and trigger at its extreme rear, is difficult to manipulate when mounted as above described. The gunner is cramped and because of his cramped position he cannot quickly register on the target nor easily operate the trigger of the gun. Furthermore, the swinging of the gun to the right or left or the elevation or depression thereof, brings the trigger into a position such that it can be manipulated only with difficulty. Also, because of the fact that aviators must of necessity wear heavy mittens or gloves, it is practically impossible for them to operate the trigger with which guns of this type were provided, since the trigger is operated by pulling it with a finger.

It is the object of this invention to provide a trigger or firing control of such a character that it adapts itself to the position of the gun so that it may readily be operated in any position the gun may assume, and to so place the firing control that the gunner will not have to assume a cramped and unnatural position in firing the gun; and also to provide a trigger which can be operated by pressure exerted either by the whole hand or by the thumb.

Referring now to the drawings,—

Fig. 1 is an end elevation of the gun mounted in a universal support;

Fig. 2 is a longitudinal sectional view through the receiver, showing the breech-bolt in firing position;

Fig. 3 is a transverse sectional view of the receiver, showing the rear end of the breech-bolt in elevation and the trigger in section;

Fig. 4 is a section on line 4—4 of Fig. 3; and

Fig. 5 is a section on line 5—5 of Fig. 4.

Fig. 1 shows a way in which a gun may be mounted so as to be capable of practically universal movement. The gun 1 is carried by a circular head 2 which is seated in a ring 3 in which it is free to rotate. The ring 3 is trunnioned in the supports 4 and is capable of rotation. The gun is therefore capable of movement about both vertical and horizontal axes. Pivoted on the left and right hand sides of the gun are the handles 5 and 6, respectively, which will be described in detail later.

Reciprocatively mounted in the receiver 7 is the breech-bolt 8 which is provided with the firing-pin 9, the lever 10, sear 11 and sear spring 12 all of which are well known in a gun of this type. The sear 11 has an angular-shaped head 13 which engages a coacting depression in the inner end of the sear slide 14, which is reciprocatively mounted in the rear end of the breech-bolt at right angles to the sear. An inward movement of the sear slide depresses the sear, disengaging the same from the firing-pin, allowing the latter to spring forward and explode a cartridge.

The receiver is cut away to form the slot 15, which has the under-cut surfaces 16 at either end. Fitting over this slot is the plate 17 which has a lug 18 cut to engage with one under-cut surface 16 and a bolt 19 with a properly shaped head 20 to engage the other under-cut. On the inner surface of the plate is cut a circular depression 21 in which is rotatably seated the head 22 of the bushing 23, the shank of which extends through the plate. The handle 5 is firmly attached to the bushing. Reciprocatively mounted in the handle and concentric with the bushing 23 is the pin 24, the inner end 25 of which is conical. Pivoted in the

handle on the pin 26 is the bell-crank lever 27, one end of which is connected to the outer end of the pin 24. The other end of the lever 27 is attached to the rod 28 at the outer end of which is the head 29. In a suitable housing 30 at the opposite end of the handle is contained the spring 31 which bears against the collar 32 of the rod 33 the exposed end of which engages the larger arm of the lever 27 and serves to normally hold the pin 24 in the position shown in Fig. 4.

A pin 34 may be carried by the head 22 to engage stops 35 to insure the maintaining 15 of the handle 5 in such a position that the head 29 of the rod 28 will always be readily accessible.

In operation, the gunner grasps both of the handles 5 and 6 and points the gun in 20 any desired direction. As the rear end of the gun is elevated or depressed, the handles 5 and 6 turn to accommodate themselves to the gunner's hands. When it is desired to fire the gun, the operator pushes 25 in the rod 28 with his thumb or with the palm of his hand. This causes the pin 24 to operate the sear slide which, in turn, disengages the sear from the firing-pin, allowing the latter to spring forward and explode the 30 cartridge. The gun will now go through its cycle of operations until the bolt gets back to firing position. If, during this cycle, the rod 28 has been released, the gun will not fire again. But if the rod 28 is held 35 in, the gun will fire automatically. This is caused by the engagement of the end of the sear slide with the conical point 25, which results in the inward movement of the sear 40 slide and the consequent release of the firing-pin.

While the drawings in this application illustrate the invention as applied to an automatic gun of the heavy Browning type, I do not limit myself to the use of this invention in connection with said type of gun, but claim it in its application to any gun in which conditions make my invention applicable.

What I claim is,—

50 1. In an automatic gun, a firing-pin, means for retaining said firing-pin in inoperative position, means for releasing said re-

taining means, a handle pivotally mounted on the gun, and means in said handle operable in any position thereof to actuate said 55 releasing means, said means including a pin reciprocatively mounted in said handle.

2. In an automatic gun, a firing-pin, means for retaining said firing-pin in inoperative position, means for releasing said 60 retaining means, a handle pivotally mounted on the gun, and means in said handle operable in any position thereof to actuate said releasing means, said means including a tapered pin reciprocatively mounted in said 65 handle.

3. In an automatic gun, a handle rotatably mounted on the side thereof, a trigger reciprocatively mounted in said handle, and means to operate said trigger in any position of the handle. 70

4. In an automatic gun, a handle rotatably mounted on the side thereof, a trigger having a tapered head reciprocatively mounted in said handle, and means to operate said trigger in any position of the handle. 75

5. In an automatic gun, a handle rotatably mounted on the side thereof, a trigger reciprocatively mounted in said handle, and means including a rod reciprocatively mounted in said handle to operate said trigger. 80

6. In an automatic gun, a breech-bolt, a firing-pin, a sear and sear-slide operatively 85 mounted in said bolt, a handle pivotally mounted on the gun, and a pin reciprocatively mounted therein in alinement with the sear-slide.

7. In an automatic gun, a breech-bolt, a firing-pin, a sear and sear-slide operatively 90 mounted in said bolt, a handle pivotally mounted on the gun, a pin reciprocatively mounted therein in alinement with the sear-slide, and means to operate said pin. 95

8. In an automatic gun, a breech-bolt, a firing-pin, a sear and sear-slide operatively mounted in said bolt, a handle pivotally mounted on the gun, a pin reciprocatively mounted therein in alinement with the sear-slide, a push-rod in said handle, and a bell-crank lever connecting the adjacent ends of the pin and push-rod. 100

HUGH M. ROCKWELL.
